UNITED STATES PATENT OFFICE.

STEPHAN PFEIFFER, OF ST. PILT, NEUBAU STATION, RIBEAUVILLE CIRCLE, UPPER ALSACE, FRANCE, ASSIGNOR TO CHARLES KOLLER AND CHARLES FREYSZ, BOTH OF STRASBURG, ALSACE, FRANCE.

HAND PLANE.

1,417,857.

Specification of Letters Patent. Patented May 30, 1922.

Application filed June 23, 1920. Serial No. 392,493.

(GRANTED UNDER THE PROVISIONS OF THE ACT OF MARCH 3, 1921, 41 STAT. L., 1313.)

To all whom it may concern:

Be it known that I, STEPHAN PFEIFFER, residing at St. Pilt, Neubau Station, Ribeauville Circle, Upper Alsace, France, have invented certain new and useful Improvements in or Relating to Hand Planes (for which I have filed applications in Germany, Jan. 22, 1916, No. 327,646; France, Feb. 27, 1919, No. 522,925; Great Britain, Oct. 30, 1919, No. 134,547; Belgium, Sept. 8, 1919; Luxembourg, Sept. 9, 1919, No. 11,497; Switzerland, Sept. 9, 1919, No. 35,256; Italy, Sept. 9, 1919, No. 187/513; Tunis, Sept. 13, 1919, No. 1,627; Spain, Sept. 11, 1919, No. 70,848; Denmark, Sept. 16, 1919, No. 26,791; Morocco, Sept. 16, 1919, No. 125; Norway, Sept. 20, 1919; Austria, Sept. 25, 1919; Hungary, Oct. 25, 1919; Portugal, Sept. 25, 1919, No. 10,998; Sweden, Sept. 27, 1919, No. 50,311; Japan, Sept. 21, 1920, No. 37,203), of which the following is a specification.

There are already planes in existence in which the plane iron, sliding over a rigid metal plate lodged in the stock and clamped by means of a tightening handle, is displaced in the direction of its longitudinal axis by means of a screw. But these planes have the defect that the rigid plate forming a guide, together with the screw that displaces the plane iron in the direction of its longitudinal axis, and the tightening handle, take up a great deal too much room in the stock and necessitate inconvenient auxiliary parts. They also present the disadvantage that the metal plate or guide, and also the other members of the plane, cannot be arranged so deeply in the stock, and finally that the mounting of the tightening handle and of the screw that displaces the iron longitudinally in the plane is not sufficiently strong and rigid, both as regards the relative position of these members and as regards their position with respect to the guide plate and to the iron. Finally the acting part of the tightening handle is too far from the cutting edge of the iron and the tightening is effected by means of intermediate members located in the path of the shavings and hindering them from passing out.

Planes of this type are also often provided with a device enabling the plane iron

to be displaced laterally. This device is located, in consequence of the lack of room already mentioned, too far from the cutting edge of the iron, and can only act on the iron through the medium of intermediate members, which prevents an accurate transverse adjustment of the plane iron from being obtained.

The present invention relates to a plane which obviates the disadvantages pointed out above, thanks to the arrangement of a plate forming a guide, which, in addition to an upper wing and a lower wing intended for the purpose of supporting the screw that displaces the plane iron longitudinally, also possesses lateral wings for the mounting of the tightening lever of the iron, and which moreover makes it possible to locate the device that effects the transverse displacement of the plane iron deeply in the stock and below the axis of rotation of the iron, and to arrange it in such a way as to act directly on the iron. It follows from this that the force that effects the transverse displacement of the iron has its point of application as near as possible to the cutting edge thereby making it possible to adjust the transverse position of the iron with a slight effort.

In the accompanying drawings one constructional form of the subject-matter of the invention is illustrated by way of example.

Figure 1 is a longitudinal section of the plane.

Figure 2 is a plan of the plane, from which the plane irons have been removed.

Figure 3 shows the device for the lateral displacement of the iron.

In these figures, 1 and 2 are the plane iron and the break iron, which are both displaced by the nut 3 and the screw 4. The nut 3 is provided with a nipple 5 which enters a suitable hole in the plane iron or blade 1. The adjustment of the relative positions of the cutting iron and the break iron is effected by means of a screw 6. The irons 1 and 2 are pressed against one another and against the guide plate 7 by means of a hand lever 8 which can be turned down and which pivots for this purpose about the two trunnions 9 located in the wings 10 of the guide plate 7. The lever 8 is provided

with two lever arms and is formed in such a way that its shorter arm 11 (Figure 1) presses the irons 1 and 2 against the guide plate 7, when it is in the position shown in Figure 1. By bringing the longer arm of the lever into the position shewn in dotted lines the irons are loosened and they can then be withdrawn from the plane. Since the tightening handle or lever is itself mounted on the guide plate it forms with the cutting iron and the top iron and the guide a virtually integral unit which will strongly resist the stresses to which it is subjected by the work to be done.

In order that the upper end of the adjusting screw 4 may be quite free and may be able to take any actuating member, such as a wing nut, the guide is provided with two wings 12. These wings serve as supports for the two extremities of the adjusting screw 4 so that it may be held firm in order to prevent any displacement thereof and so that the nut may move without jamming during the adjustment. The fixing of the guide on to the plane stock 13 may be effected for example by means of the screws 14 (Figure 2). In consequence of the arrangement of the wings 12 the upper extremity of the screw 4 passes freely to the outside and since there is no obstacle in the path of the said extremity it is possible to mount thereon an actuating member provided with a long lever arm, which in the present case will take the form of a wing nut 15, thereby enabling the plane iron to be displaced without the use of any auxiliary tool and without first having to turn down the lever 8. Thanks to this arrangement it is possible to locate the guide rather deeply in the plane stock and the guide moreover does not take up much room. Furthermore, it is possible to place a nut 17 with a lock nut 18 on the part 16 of the screw 4 above the wing 12 of the guide 7. By means of these nuts it will be possible to take up at once any play that might be produced in the mounting of the screw 4. The lock nut prevents the nut 17 from working loose, and it is this nut 17 which really effects the adjustment.

In order to be able to displace and regulate accurately the transverse position of the plane iron 1 and of the top iron 2 a bolt 19 (Figures 1, 2 and 3) is arranged perpendicularly to the longitudinal axis of the plane in a special cavity in the plane stock below the axis of rotation 5 of the plane iron, this bolt being screw-threaded at 20 on the part of its length that engages in a nut 21 fixed in any suitable manner into the cheek of the plane stock. The bolt 19 is turned down to a smaller diameter along a part corresponding to the width of the iron 1, so as to form two shoulders 22 between which the irons are placed and guided. It will therefore be

seen that by rotating the bolt 19 by means of the butterfly nut 23 in one direction or the other there will be immediate transverse displacement of the bolt and also of the plane irons carried along by one or the other of the collars 22, the transverse position of the iron thus admitting of being regulated easily, conveniently and with the utmost exactness, for the force acting is applied near the cutting edge of the blade.

The means described consequently form a device which is of the simplest and most reliable character and which enables the irons to be displaced without the help of any auxiliary tool and without first having to loosen them, and furthermore makes it possible to take up any play of the adjusting screw which might be produced and furthermore to effect an accurate transverse adjustment of the iron. It will also be seen that the extreme simplicity of the members of the plane answers perfectly for manufacture in quantities, thereby enabling this plane to be produced at a moderate cost price.

What I claim and desire to secure by Letters Patent of the United States is:—

1. A plane in which the iron sliding over a rigid metal guide is clamped in position by means of a lever and can receive displacements in the direction of its longitudinal axis, the plane being characterized by the fact that besides the upper and lower wings at right angles, which serve as a support for the screw that displaces the blade longitudinally, the guide is provided with lateral wings or cheeks for the mounting of the tightening lever, while underneath the nipple of the nut which serves to displace the iron longitudinally and which also serves as a point of articulation for the transverse displacement of the iron a transverse bolt is mounted in such a way as to be able to rotate and at the same time to move transversely to the longitudinal axis of the plane, and this bolt, in moving, acts directly on the iron and displaces it transversely.

2. In the plane specified in claim 1, the arrangement of shoulders turned down on the bolt which serves for the transverse adjustment and which moves in the plane stock by screwing the said shoulders acting, when the said bolt is rotated, on the iron, which they embrace.

3. A constructional form of the plane specified in claims 1 and 2, characterized by the arrangement of a nut on the narrowed part of the screw that produces the longitudinal displacement of the iron, located above the upper wing of the guide, this nut making it possible to take up the play that might be produced by the movement of the said screw, and being capped by a lock nut which prevents it from working loose.
